UNITED STATES PATENT OFFICE.

JOHN R. TOWNSEND, OF SOUTH BEND, INDIANA, ASSIGNOR TO WESTINGHOUSE ELECTRIC & MANUFACTURING COMPANY, A CORPORATION OF PENNSYLVANIA.

DESIGN FOR A POST-TOP LANTERN.

Application filed September 22, 1925. Serial No. 14,852. Term of patent 14 years.

To all whom it may concern:

Be it known that I, JOHN R. TOWNSEND, a citizen of the United States, residing at South Bend, in the county of St. Joseph and State of Indiana, have invented a new, original, and ornamental Design for a Post-Top Lantern, of which the following is a specification, reference being had to the accompanying drawing, constituting a part hereof.

The figure is an elevational view of a post top lantern showing my new design.

I claim:

The ornamental design for a post top lantern as shown.

In testimony whereof, I have hereunto subscribed my name this 24th day of August, 1925.

JOHN R. TOWNSEND.
